UNITED STATES PATENT OFFICE

96,531

DESIGN FOR A CLOWN-TYPE DOLL

Joseph Coyle, Chicago, Ill.

Application October 1, 1934, Serial No. 53,448

Term of patent 7 years

To all whom it may concern:

Be it known that I, Joseph Coyle, a citizen of the United States, residing at Chicago, in the county of Cook and State of Illinois, have invented a new, original, and ornamental Design for a Clown-Type Doll, of which the following is a specification, reference being had to the accompanying drawing, forming part thereof.

I claim:

The ornamental design for a clown-type doll, as shown and described.

JOSEPH COYLE.
